UNITED STATES PATENT OFFICE.

HAROLD T. BLUM, OF GLENMONT, OHIO.

SWEATBAND FOR HEAD COVERINGS.

Original application filed June 23, 1927, Serial No. 201,002. Divided and this application filed September 19, 1927. Serial No. 220,546.

This invention relates to improvements in sweat bands for that type of head coverings generally identified in this art as caps, the improvement constituting a division of my 5 copending application for United States Letters Patent filed by me June 23, 1927 bearing serial number 201,002, having for an object to provide a head covering sweat band of such construction and shape as will effect 10 snug engagement with and over the major portion of the hair upon the head of a wearer of an equipped cap, whereby to insure the retention of such hair in properly combed or groomed position and against undesirable 15 disarrangement, means being supplied portions of the band for yieldably retaining the opposite side and head engaging portions of the same in substantially concavo-convex formation whereby said portions will be permitted 20 to automatically adjust themselves to the head and hair of a wearer of the equipped cap without discomfiture and at the same time, insure the aforesaid hair retention engagement.

25 Other objects of the invention will be in part obvious and in part pointed out hereinafter.

In these drawings,

Figure 1 is a bottom plan view of the improved sweat band showing it applied to a cap and

Figure 2 is a vertical transverse section through the same.

Having more particular reference to the drawings, in connection with which like characters of reference will designate corresponding parts throughout, I have chosen for illustration in this particular embodiment of the invention a receiving body for the improved 35 sweat band in form of that type of head covering generally known in the art as a cap, the said head covering being herein indicated in its entirety by the numeral 1 and, as is usual, being formed with a circular head engaging portion about and within which a sweat band generally indicated by the numeral 2 is engaged, portions of said band being arranged adjacent or in substantially parallelism to the edge or marginal portion of the 45 head receiving opening of the cap 1 whereby to permit of stitching or other suitable form of joinder of the band to the cap body, as may be desired.

This sweat band 2 is preferably composed

of leather, imitation leather, fabric or of other suitable material possessing the necessary qualities of durability, moisture resistance and pliability and as is shown in the Figure 1, the forward and rearward head engaging portions of the band are comparatively narrow as is indicated by the numerals 3 and 4, while the opposite side and head engaging portions of said band are materially widened as is indicated by the numerals 5 and 6, the respective widths of said portions 5 and 6 being entirely regulated according to the size of the particularly equipped hat, although for example, it may be stated at this point that in the standard size number 7 of the head covering, the portions 5 and 6 are, through their widest parts, substantially five inches, the said widened parts gradually diminishing in width as they approach and extend into the narrower forward and rearward head engaging portions 3 and 4, aforesaid.

The widths of the widened portions 5 and 6 of the head band 2 are such as to insure of engagement of their inner faces over the major portion of the hair upon the head of a wearer of the equipped cap and with a view toward effecting a snug, form and curvature following engagement of these widened portions 5 and 6 with the wearer's head and hair, spring forms, ribs or stiffeners designated herein by the numeral 7 are employed, one of the same being arranged upon each of the said widened portions 5 and 6 as is shown in the Figure 1, preferably, being disposed transversely of the intermediate parts thereof and having their free or opposite extremities joined to adjacent portions of the band by stitching or other suitable process or means whereby to avoid displacement of the same.

The spring forms or stiffeners 7 may be formed of any suitable material possessing the desired or necessary degree of resiliency such as to insure comfort when arranged upon the head of a wearer of an equipped cap and herein, it will be understood that said devices may be constructed of certain forms of metal, bone, plastic material, etc., such as conditions or preference may dictate; the said forms being concavo-convex in formation as is shown in the Figure 2 whereby with arrangement of the same and their connection to the widened portions 5 and 6 of the band 2, they will impart a similar concavo-convex formation to the band, retaining it in that

general position or shape as is shown in the said Figure 2, so that with engagement of the cap upon a wearer's head, the curvature of the head will be followed by the widened portions of the band and consequently, thereupon, a snug engagement of such band with the major portion of the wearer's hair will be insured, hence, retaining such hair in properly combed or groomed position against undesirable disarrangement or mussing. Furthermore, by reason of the concavo-convex supporting and forming of the widened parts 5 and 6 of the sweat band 2, it will be understood that the top or upper side of the cap body portion 1 will be maintained out of engagement with the wearer's hair and because of this, its retention in that condition as hereinbefore explained will be further assured during placement of the cap upon a person's

head, the adjustment thereof subsequently to placement or removal from the head. 20

I claim:

A combined sweat band and hair retainer for caps comprising a body of flexible material secured to the cap within the head receiving opening thereof, and adapted to have snug engagement throughout its area with the head of the wearer, said body having a restricted front and back portion and widened side portions, and a stiffening element associated with each widened side portion of the body and adapted to urge and hold said portions in close engagement with the head of the wearer. 25 30

In witness whereof I have hereunto set my hand. 35

HAROLD T. BLUM.
